UNITED STATES PATENT OFFICE.

THOMAS DANQUARD, OF NEW YORK, N. Y., ASSIGNOR TO THE AUTO PNEUMATIC ACTION COMPANY, A CORPORATION OF NEW YORK.

SOFT-TENSION-GRADUATING DEVICE FOR MUSICAL INSTRUMENTS.

1,287,649.

Specification of Letters Patent.

Patented Dec. 17, 1918.

Application filed October 5, 1914, Serial No. 865,026. Renewed April 5, 1917. Serial No. 159,860.

To all whom it may concern:

Be it known that I, THOMAS DANQUARD, a citizen of the United States, residing at New York, in the county of New York and 5 State of New York, have invented a new and useful Soft-Tension-Graduating Device for Musical Instruments, of which the following is a specification.

This invention relates to a device for 10 graduating the air pressure of a musical instrument and the principal objects thereof are to provide an extremely simple and inexpensive means by which an ordinary regulating means for softening the tension can 15 be augmented either by one step, or a plurality, so that two or more different degrees of tension can be secured; and especially to arrange these parts in such a way that they add very little to the expense of manufacture and assemblage of the parts of the instrument, and to the space occupied. The invention is applicable to various kinds of 20 musical instruments operated pneumatically.

Reference is to be had to the accompanying 25 drawings in which—

Figure 1 is a longitudinal central sectional view of the connections between the main bellows and action of a musical instrument showing a preferred form of this invention 30 connected therewith;

Fig. 2 is an elevation of the same with parts removed to show interior construction, and

Fig. 3 is a sectional view on the line 3—3 35 of Fig. 2 on reduced scale.

The invention is shown as applied to an instrument in which there is a main wind-way 10 connecting the main bellows (not shown) through a port 11 with the action 40 through a tube 12. Between the wind-way 10 and the tube 12 is a slidable valve 13 adapted to close a port 14 and thus stop the connection between these two parts as is well understood in this art, this valve being 45 closed when it is desired to reroll and in some other cases.

Between the ports 11 and 14 are two passages 15 and 16 separated from each other and adapted to be connected through a port 50 17. This port is controlled by a valve 18

and can be entirely closed thereby. When this valve is closed the air from the tube 12 passes along the channel 16 into a pneumatic 20 and out from the same into the channel 15. The port connecting the channel 15 with the interior of the pneumatic 20 is controlled by a valve 21 which is so connected with the movable leaf 22 of the pneumatic that it will be brought nearer to its seat whenever the pneumatic starts to collapse. In this way a choking action is secured and the tension or pressure, as it is called, on the action is reduced.

I have shown the casing as provided with two cleats 26 each connected with an arm 23 by a spring 24 which is removably attached to the arms by a small pivoted catch 25. The arms 23 are secured to the movable leaf, thus normally tending to hold the pneumatic in its expanded condition by spring action.

What has been described above can be used to soften the tension on the action but by its use alone, there are only two conditions, the full tension and the reduced tension. This invention has mainly to do with 75 means whereby the pneumatic 20 can be still further collapsed to different degrees so that the choking action can be increased. In the form shown in the drawings, three different degrees of reduced tension are secured in addition to the full tension. For this purpose, to the movable leaf 22 in this pneumatic are positively fixed by means of two bars 27 and 28 two additional movable leaves 29, constituting parts of the auxiliary 80 pneumatics 30 and 31 respectively.

Projecting into the interior of the main regulating pneumatic 20 is a ledge 32 having two pouches 33 therein each connected by a channel 34 with a tube 35. One of these tubes is connected with a channel 36 and the other with a channel 37 having ports 38 and 39 respectively located in a plate 40 and adapted to be uncovered by a valve 41. This valve is arranged to slide with the valve 18, 95 being connected therewith by a handle 42 and being operated in any desired ordinary way. The port 39 is in advance of the other port 38 so that when the valve is moved the port 39 is opened first. On further move- 100

ment of the valve in the same direction the other port 38 is uncovered. The relationship of the valve 41 and the valve 18 is such also that the valve 18 will be fully closed 5 upon motion of the valve rod 42 before either of the ports 39 or 38 is opened. Thus a continuous motion in that direction will first close the port 17, then open the port 39 and finally open the port 38.

10 The closing of the port 17, as has been stated, causes a reduced tension to be applied to the action on account of the motion of the movable leaf 22 and the valve 21. When the port 39 is opened by the further motion 15 of the valve stem 42 air will be admitted into one of the tubes 35 and into and behind one of the pouches 33, the other side of which is open to the suction. This causes the pouch to move outward by expansion 20 and a double valve 44 to move with it. This opens a port 45 and connects a passage 46 with the interior of the pneumatic 20 and shuts this passage off from the communication with the exterior air through a port 47. 25 This channel 46 communicates through a port 48 with the auxiliary pneumatic 31 and consequently this is connected with the suction and collapses. On account of its movable leaf being fixed to the movable leaf 22 30 it assists in the collapsing of the latter by adding to the area of the effective action of the suction. Thus the regulating pneumatic 20 will be further collapsed and the valve 21 brought nearer to its seat. In this way 35 the tension on the action is further reduced and thus we get a second graduation of the reduction of the pressure.

The other auxiliary pneumatic 30 is operated in exactly the same way on the opening 40 of the port 38 and reduces the tension still further so that we get another degree of tension. The number of different degrees of tension will depend of course upon the 45 number of these auxiliary pneumatics that are employed within the principle of this invention.

Although I have illustrated and described only a single form of the invention I am aware of the fact that many modifications 50 can be made therein by any person skilled in the art without departing from the scope of the invention as expressed in the claims. Therefore I do not wish to be limited to the details of construction herein shown or described, nor to any particular type of musical instrument, but what I do claim is:—

1. In a pneumatic tension graduating device, the combination of a pneumatic, a tension graduating valve controlled thereby, an 60 auxiliary pneumatic connected with the first named pneumatic directly for assisting its collapse, and means for connecting the auxiliary pneumatic with a source of air tension to set it into operation.

65 2. In a pneumatic tension graduating de-

vice, the combination of a pneumatic, a tension graduating valve controlled thereby, an auxiliary pneumatic connected with the first named pneumatic for assisting its collapse, and manually controlled means for connecting said auxiliary pneumatic with the interior of the first named pneumatic to assist its operation.

3. In a pneumatic tension graduating device, the combination of a pneumatic, a tension graduating valve controlled thereby, a plurality of auxiliary pneumatics connected with the first named pneumatic for assisting its collapse, and means for connecting the auxiliary pneumatics successively in fixed 75 sequence with a source of air tension to set them into operation.

4. In a pneumatic tension graduating device, the combination of a pneumatic, a tension graduating valve controlled thereby, a plurality of auxiliary pneumatics connected with the first named pneumatic for assisting its collapse, and means for first causing all air passing from the action to the wind way to pass through the first named pneumatic, 80 and thereafter connecting said auxiliary pneumatics in succession with the interior of the first named pneumatic.

5. In a musical instrument, the combination with a tube for conducting air from an action, a main wind-way, and means for conducting air from one to the other, of a pneumatic, means for conducting the air through the pneumatic for the purpose of reducing the air tension on the action, a second pneumatic, the movable leaf of which is fixed to the movable leaf of the first pneumatic, and means for connecting the second pneumatic with a source of air tension for the purpose of causing it to collapse in unison with the first pneumatic and increasing 100 the reduction of tension.

6. The combination with a main wind-way, means for conducting air from an action to the wind-way, and a valve for choking the tension, of a pneumatic adapted to be connected with said means and adapted to be collapsed when connected therewith, the movable leaf of which constitutes means for moving said valve into its choking position, 115 a second pneumatic, the movable leaf of which is fixed with respect to the first named movable leaf, and means whereby the second pneumatic can be connected with a source of air tension, whereby both pneumatics will 120 operate together and still further close said valve.

7. The combination with a main wind-way, means for conducting air thereto from an action, a regulating pneumatic, a passage 125 from the main wind-way to the regulating pneumatic and back to the action, a valve for closing the first named means to cause the air to traverse said passage, and a valve in said pneumatic adapted to regulate the 130

amount of air passing through said passage, of a plurality of auxiliary pneumatics, the movable leaves of which are connected with the movable leaf of the first named pneumatic, and means whereby the auxiliary pneumatics can be connected one at a time with a source of air tension whereby they will assist the leaf of the first named pneumatic and increase the choking action of said valve in different degrees according to the number of said auxiliary pneumatics that are so connected.

8. In a self-playing musical instrument, an expression-governing device having a tension controller normally set to produce a certain tone effect, and means for subduing the tone including separate pneumatic assisters for exerting closing force upon the controller to reduce the air tension and means for energizing said assisters one by one in sequence.

9. In a self-playing musical instrument, an expression-governing device including a pneumatic having yielding means for opening it with a force substantially equal to that of the air tension therein necessary to produce a certain tone effect, and pneumatic means for exerting a closing effect upon the first-named pneumatic against the action of said opening means.

10. In a self-playing musical instrument, an expression-governing device including a pneumatic, a spring normally opening said pneumatic with a force sufficient to counteract that of the air tension therein necessary to produce a certain tone effect, separate pneumatics for opposing the action of said spring, and means for energizing said last-named pneumatics individually and collectively.

11. In a self-playing musical instrument, an expression-governing device including a pneumatic, yielding means for opening said pneumatic under a predetermined force sufficient to cause the production of loud tone effects, a pneumatic assister for exerting closing pressure upon the first-named pneumatic against the action of the opening means to cause the production of softer tone effects, and means for energizing said pneumatic assister.

12. In a self-playing musical instrument, an expression-governing device including a pneumatic, means for opening said pneumatic with a predetermined force sufficient to cause the production of loud tone effects, an auxiliary pneumatic acting upon the movable side of the first-named pneumatic against the action of said opening means to cause the production of softer tone effects, an exhaust chamber, and means for opening and closing communication between the exhaust chamber and said auxiliary pneumatic.

65 13. In a self-playing musical instrument,

an expression-governing device including a pneumatic and yielding means for holding said pneumatic open under a predetermined force, in combination with an auxiliary pneumatic acting upon the first-named pneumatic in opposition to its opening means, an atmosphere port communicating with the auxiliary pneumatic, an exhaust port, and means for alternately placing the atmosphere port in communication with the exhaust port and with the atmosphere to cause the operation of the auxiliary pneumatic.

14. In a self-playing musical instrument, an expression-governing device including a pneumatic and means for opening the same under a force sufficient to cause the instrument to play with a certain tone effect, in combination with an auxiliary pneumatic acting upon the first-named pneumatic in opposition to said opening means, an exhaust chamber, and means for placing the auxiliary pneumatic in communication with the exhaust chamber.

15. In a self-playing musical instrument, an expression-governing device including a pneumatic, and means for opening the same under a force sufficient to cause the instrument to play with a certain tone effect, in combination with an auxiliary pneumatic acting upon the first-named pneumatic in opposition to said opening means, an exhaust chamber, and means for alternately placing said auxiliary pneumatic in communication with the exhaust chamber and with the atmosphere.

16. In a self-playing musical instrument, an expression-governing device including a pneumatic and means for opening the same under a force sufficient to cause the instrument to operate with a certain tone effect, in combination with an auxiliary pneumatic acting upon the first-named pneumatic in opposition to said opening means and normally in communication with the atmosphere, an exhaust chamber, and means for cutting off communication between the auxiliary pneumatic and atmosphere and placing it in communication with the exhaust chamber.

17. In a self-playing musical instrument, the combination with a wind-inducing device having means for communication with a sound-producing action, of means subject to operation by the air tension of said device for throttling such communication, and a spring opposing the operation of the last-named means with a force substantially equal to that of the air-tension required to produce loud tone effects.

18. In a self-playing musical instrument a pneumatic having means for communication with a wind-inducing device and a sound-producing action and subject to operation by air tension therein, means

120
125
130

1
actuated by said pneumatic for throttling communication with the sound-producing action, and a spring opposing the action of said pneumatic under a force substantially equal to that of the air tension required to produce loud tone effects.

5 In testimony whereof I have hereunto set

my hand, in the presence of two subscribing witnesses.

THOMAS DANQUARD.
